Alvin Fischstein
ATTORNEY

UNITED STATES PATENT OFFICE.

LOUIS PROPP, OF NEW YORK, N. Y.

DECORATIVE ILLUMINATING DEVICE.

Application filed July 6, 1927. Serial No. 203,761.

This invention relates to a decorative illuminating device, more specifically to a device of the character used for the purpose of ornamenting birthday cakes and the like.

In the ordinary ornamentation of birthday cakes and the like, the burning of candles thereon presents the great disadvantage that the melted tallow or paraffin runs down or falls upon the cake, with resultant unsanitary conditions. Furthermore, the beautiful spectacle sought to be derived from the use of candles is marred by the drip upon the candles, and the spotted condition of the top of the cake. Then again, the duration of the effect of ordinary candles is limited by the size of the candles. In addition, some candles burn faster than others so that an uneven appearance is presented to the eye after a short period of use which detracts from the desired decorative effect.

It is the purpose of this invention to provide a device, simple of construction and easily assembled in which all of these defects are eliminated.

Furthermore, a construction is provided, applicable to birthday cakes of different sizes, by means of which the effect of vari-colored candles, of varied numbers of candles, of various sizes of candles, and of flowered decorations may be obtained.

A further object is to present an illuminating device for birthday cakes in which an ornamental support is provided for maintaining said device with respect to various sizes of cake or the like.

Other objects of this invention will in part be obvious and in part hereinafter pointed out.

The invention accordingly consists in the features of construction, combination of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a side elevational view of an embodiment of the invention, showing it mounted about a cake;

Fig. 2 is a plan view of the device, with some of the lights removed;

Fig. 3 is an enlarged side elevational view of a portion of the embodiment, parts being

broken away to illustrate the adjusting means and electrical connections;

Fig. 4 is a wiring diagram for a set-up in which twenty-four lights are used;

Fig. 5 is a sectional view of a modification of the supporting and adjusting means; and

Fig. 6 is a sectional view of an additional modification.

On the drawings, 10 indicates an embodiment of the invention in which a flat, circular base 11, which carries the decorative features hereinafter described, is supported by means of columns 12 over a cake 13 of the type ordinarily provided for festive occasions. The base 11, made of wooden or any other material, easily cut and shaped and painted in an ornamental manner, is made up of two sections 11^a and 11^b, section 11^b being separable from section 11^a. Section 11^b has formed in its under surface the circular grooves 14, 15 and 16, these grooves having communication with a passage 17, likewise formed in the under surface of section 11^b, in which passage and grooves are adapted to be housed the conductor wires 18 for the illuminating features to be described. These grooves are provided with openings 19 into which are fitted the ordinary sockets 19^a for the reception of standard electrical fixtures or lights.

As shown in Fig. 1, these openings are so spaced that a pleasing appearance will be presented and so that an easily variable arrangement of lights may be produced. It is possible to insert in these sockets 19^a ornamental lights of any type, as shown at 20, or the standard candle light of the trade which, as shown in Fig. 3 at 21, may be built up to any desired height to present the appearance of a very large candle. Single lengths may be inserted into the other sockets to display smaller candles 22.

In order that the device may utilize the miniature small voltage electric bulb ordinarily provided for Christmas tree ornamentation and the like, the device is wired in a manner shown by the wiring diagram in Fig. 4 so that eight bulbs will be in series to be supplied by the normal house line voltage.

To make this device easily applicable to different sizes of cake, the columns 12 are provided with means for varying the effective circumference of the supporting means and also the effective height of the plate 11.

The horizontal varying means is embodied in the slot 23 formed in the upper section 24 of the column 12. Screw 25 which retains this upper section 24 secured to section 11^a also provides a ready means for allowing section 24 to be moved toward and away from plate 11 within a limited distance.

Section 24 is formed with a downturned leg 26 having a slot 27 in which is slidably mounted an adjustment screw 28 which is received in the lower section 29 of column 12 at screw hole 30. Section 29 is formed with an outturned foot 31 for properly supporting the apparatus and projecting lug 29^a formed integral therewith, said lug being received in slot 27 to provide a stop means for limiting movement of the sections 29 and 24 with relation to each other, and further providing means for giving rigidity to column 12 in conjunction with screw 28.

By means of screw 28, the relation of leg 26 and section 29 may be fixed, or screw 28 having been loosened the relation of sections 24 and 29 may be varied so that the height of base 11 may be adjusted within a limited range.

In Fig. 5 is disclosed a modification of column 12 for adjustably supporting base 11, as indicated at 112, in which a base 32 is formed with an upwardly extending, preferably integral cylinder 33, encasing a threaded rod 34 secured to base 32. Threadedly mounted on rod 34 is an internally threaded cylinder 35 which by means of a lug 36, is mounted on an upper section 124 which upper section is provided with a slot 123 to coact with screw 25 on plate 11 in the manner described above as to section 24. By this arrangement, the effect of an artistic column may be presented, thus enhancing the beauty of the entire device.

In Fig. 6, a further modification is presented in which cylinder 133 attached to base 132 is internally threaded to receive the threaded portion 36 at the end of the smooth rod 37, said rod 37 being attached to the upper section 224 which is associated with the screw 25 for horizontal adjustment.

In the construction presented above, it is possible to vary the movement of candles 21 and 22 to indicate ages within certain limits and it is further possible by means of decorative lights 20 to present an artistic effect not before produced.

It will thus be seen that there is provided a device in which the several objects of this invention are achieved, and which is well

adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. A decorative lighting device for a cake or the like object, comprising a plate having upstanding lighting elements mounted thereon, and means for supporting said plate in overlying relation to such object, said means comprising a plurality of spaced members having radially extending portions secured to said plate and vertical portions adapted to rest on a base, said members being adjustable for accommodating objects of varying size.

2. A decorative lighting device for a cake or the like object, comprising a plate, lighting elements mounted thereon, and means for supporting said plate in overlying relation to said object, said means comprising a plurality of radially and vertically extending members secured to said plate at spaced points thereon, said members being adjustable for raising or lowering said plate to accommodate objects of varying heights, said members being further adjustable in a radial direction for accommodating objects of varying horizontal cross-sectional area.

3. A decorative lighting device for a cake or the like objects, comprising a plate, lighting elements mounted thereon, and means for supporting said plate in overlying relation to said object, said means comprising a plurality of radially and vertically extending members secured to said plate at spaced points thereon, said members being adjustable for raising or lowering said plate to accommodate objects of varying heights, said members being further adjustable in a radial direction for accommodating objects of varying horizontal cross-sectional area, said plate comprising two super-imposed sections, the upper one of said sections having a plurality of openings therein for receiving said lighting elements, one of said sections having a groove adjacent said other section for receiving the wiring for said elements.

In testimony whereof I affix my signature.

LOUIS PROPP.
